Des. 222,258
Patented Oct. 12, 1971

222,258

TOILET BOWL COVER

David E. Harrison, Columbus, Miss., assignor to Beneke
Division, Beatrice Foods Co., Columbus, Miss.

Filed July 27, 1970, Ser. No. 24,164

Term of patent 3½ years

Int. Cl. D23—02

U.S. Cl. D23—71

FIG. 1 is a top plan view of a toilet bowl cover showing my new design;

FIG. 2 is a side view thereof; and

FIG. 3 is a section taken on the line 3—3 of FIG. 1.
I claim:

The ornamental design for a toilet bowl cover, as shown.
